UNITED STATES PATENT OFFICE

ADOLPH A. THOMAS, OF NEW YORK, N. Y.

ELECTRIC PHONOGRAPH

Application filed October 8, 1926. Serial No. 140,355.

My invention relates to sound-reproducing machines, and its object is to provide an electric phonograph of novel construction and improved operation. The various features of my invention are particularly adapted to produce an electric phonograph of the small portable type and yet capable of giving a loud reproduction equal in quality and volume to that of large cabinet machines.

10 The electric phonograph of my invention uses no amplifying horn, but a large loud-speaking diaphragm is mounted in horizontal position below the motor board of the outer casing, which need not be much larger than the diaphragm itself. An inside partition divides the case or box of the machine into upper and lower compartments. In the lower compartment is the diaphragm, and the upper compartment houses the various 20 electrical devices of the reproducing circuits, such as batteries, transformers, resistances, vacuum tubes, and so forth. On the motor board are conveniently mounted certain control members by which the volume of reproduction may be regulated as desired. The diaphragm compartment has one or two swinging doors which, when open, allow the vibrations of the diaphragm to pass into the free air all around. By adjusting the position of the doors, the sound waves are deflected into the desired direction. The relative arrangement of the diaphragm and the partition above it is such that sound waves striking the partition are thrown out of the casing, 30 so that the full acoustic effect of the diaphragm is impressed upon the outer air. By using a diaphragm of sufficient size, it is possible to obtain tremendous volume from a small portable machine. The lid of the case 40 is constructed to support a number of records, which do not interfere with the mechanism above the turntable when the lid is closed.

Referring to the electrical features of my new phonograph, I may briefly mention at 45 this point the automatic control of the reproducer circuits to prevent waste of current when the machine is not in playing condition. As long as the doors of the diaphragm compartment are closed, the filament circuits of the amplifying tubes remain open. When the doors are swung open, a switch controlling the filament circuits automatically closes. As a further precaution against wasting filament and plate current, I provide an additional switch device which closes the filament circuits only when the amplifying circuit of the electromagnetic mechanism for the diaphragm is completed. In the circuit connections for electrically transmitting the needle vibrations to the diaphragm, I may use one or more amplifying tubes. A two-stage amplification is ordinarily sufficient, and I provide novel control means for using one or more stages of amplification by simply moving a finger piece on the motor board. When this finger piece is in neutral position, all battery circuits are open. All the electrical parts that comprise the amplifying system are preferably housed in separate chambers formed in the space between the motor-board and the transverse partition previously mentioned. These chambers are closed by covers mounted on the motor-board and easily moved into open position.

The various features and advantages of my invention will be fully understood from a detailed description of the accompanying drawings, which illustrate a portable electric phonograph embodying my invention. Before proceeding I want to make it clear that the particular construction here shown is merely by way of example and is not intended as a restriction or limitation of this invention, unless so specified in the claims. In these drawings—

Fig. 1 is a transverse cross-section approximately on line 1—1 of Fig. 2;

Fig. 2 represents a plan view of the machine, with the lid thrown back;

Fig. 3 is a transverse cross-section on the irregular line 3—3 of Fig. 2;

Fig. 4 shows a front view of the machine, with sections of the outer case broken away to show certain parts within;

Fig. 5 is an enlarged fragmentary view showing one of the battery chambers open;

Fig. 6 is a plan view, partly in section on line 6—6 of Fig. 4, showing the diaphragm and the doors swung open; and

Fig. 7 illustrates diagrammatically the cir-

cuit connections of the reproducing system for electrically transmitting the needle vibrations to the loudspeaking diaphragm.

The outer case or cabinet of the phonograph 5 is here shown as a cylindrical box suitable for carrying and adapted to be completely closed, like a piece of hand baggage. In its general construction, this box or case consists of a body part 10, a base or bottom 11, and a lid 10 12 for closing the top. A suitable lock holds the lid closed when the case is carried about. The base 11 is rigidly connected with the cylindrical section 10 by posts 13 and a rear panel 14. At the ends of panel 14 are hinged 15 two doors 15 and 16, the hinge connections being indicated at 17. These doors are so made that when closed they form with the panel 14 a continuous cylindrical wall, which constitutes a part of the closed outer casing. 20 The free ends of the doors abut against the front post 13, and suitable means may be provided for locking the doors or yieldably holding them in closed position. In Fig. 6 I have shown spring-pressed buttons 18 25 mounted on the base and adapted to enter recesses in the bottom of the doors.

The body section 10 of the cabinet is provided at the top with a motor-board 19 securely held in place by any practical means, 30 as by an annular ledge or shoulder 20. Within the cabinet is fixed a transverse partition 21, which is here shown as a conical disk with the apex pointing downwardly. The disk 21 thus divides the casing into an upper compartment 22 and a lower compartment 23 (see Figs. 1 and 3), which are acoustically separated from each other, or practically so. A ring 24 fixed to the body section 10 holds the disk 21 in place, or any 35 other fastening means may be used.

Over the top board 19 is mounted a turntable 25 carried on a rotary shaft 26, which is driven by a suitable motor 27, fastened to the underside of the turntable in the usual way. 40 This motor may be electrical or mechanical, and it will not be necessary to show any details of its construction. So I have merely indicated the driving motor diagrammatically by the outline 27. A stand or post 28, 45 fixed on the top board 19 at the proper place, has pivoted thereon an arm 29 carrying an electric reproducer 30 of any approved type or design. As there are several makes of electric phonograph reproducers on the market, I need not encumber the description and drawings with details of the interior mechanism of reproducer 30. It is sufficient to say here that the needle vibrations operate the reproducer to generate current impulses 50 which are amplified to operate a loudspeaker diaphragm, as will later be explained more fully. The arm 29 is so pivoted on stand 28 as to swing horizontally over a record 31 on the turntable and also to move in a vertical direction when necessary.

In the lower compartment 23 of the outer casing is mounted a loudspeaking diaphragm 32, secured at its circumference to the base 11 in any practical way, as by a clamping ring 33 suitably fastened to the base. When this ring is secured in position, it becomes part 70 of the base and part of the outer casing, as may be seen in Fig. 4. In assembling the parts of the particular construction which I am describing as an example of my invention, the diaphragm 32 and ring 33 are attached to the base before the latter is secured to the posts 13. The dotted line 34 in Fig. 6 indicates the circumferential edge of diaphragm 32, which is most conveniently 75 (but not essentially) made in conical form, like the diaphragms of the various cone speakers on the market. These diaphragms are usually constructed of paper or parchment, but they may also be of sheet metal 80 suitable for the purpose. In the space between the center of diaphragm 32 and base 11 is mounted an electro-magnetic unit 35 for actuating the diaphragm. As there are many types of such driving units on the market, 85 I need not show or describe any details of unit 35, except to say that a link or rod 36 is connected at one end to the center of diaphragm 32 and at the other end to the vibratory member of the driving unit. The 90 connection 36 may be dispensed with by providing the diaphragm with an armature arranged in operative relation to the magnetic poles of the driving mechanism. Instead of mounting unit 35 on base 11, it may be secured to the partition 21 in compartment 22. 95

The partition 21 and diaphragm 32 have small holes 37 for the passage of conductors 38 and 39, which connect the coil or coils of driving unit 35 in the amplifying circuits, 100 as presently will be described. The holes 37 are just big enough to accommodate the wires, which are so light and flexible as not to interfere with the vibrations of the diaphragm. The base 11 should have openings 40 which 105 allow the escape of air waves during the operation of the diaphragm and thereby prevent a dampening or deadening effect on the diaphragm, such as would take place if the space below the diaphragm were airtight. 110 To insure the openings 40 against closure when the machine is set down for playing, the base 11 is provided with studs or supporting lugs 41, which hold the bottom of the cabinet 115 raised. These lugs are preferably of sound-insulating material.

Referring to Figs. 1 and 3, it will be seen that the conical disk or partition 21 acts as a sound deflector for the diaphragm and tends to throw the sound waves out of the cabinet 120 in all directions. By making this deflector of resonant material like a sounding board, the vibrations of the diaphragm are strengthened. The rear panel 14 serves to deflect sound forwardly, and the doors 15 and 16 125

may be adjusted at the proper angle to concentrate the propagation of sound waves in the desired direction.

In the upper compartment 22 of the cabinet are housed all the parts and wiring that go to make up the electric amplifying system between the reproducer 30 and the driving unit 35. The number of these parts will obviously depend upon the particular amplifying system used. In the present instance, I have shown a two-stage system with means for cutting out one stage if desired. This requires two amplifying tubes, two transformers, filament and plate batteries, and certain switch mechanism. All these parts are suitably mounted in the space between the motor-board 19 and partition 21. At the present time I prefer to provide separate chambers or recesses for the transformers and batteries, so that ready access may be had to each part without removing or lifting the motor-board. Figs. 1, 2 and 3 show four of these separate chambers, as indicated by reference numerals 42, 43, 44 and 45. These chambers, which are really small boxes or frameworks, may conveniently be formed out of sheet metal or other material and secured to motor-board 19 so as to hang in compartment 22. The board 19 is cut out to leave the top of each box or chamber open. A cover 46 is provided for each box. These covers may be stamped from sheet metal and are slidably mounted between parallel guide strips 47 fastened to the motor-board, as best shown in Figs. 2 and 5. A finger piece 48 at the outer edge of each cover permits easy manipulation of the same into open and closed positions. Figs. 1 and 2 show one of the covers pushed open.

In chamber 42 is mounted a transformer 49 of suitable construction not necessary to describe. A spring clamp 50 holds the transformer securely in proper position without the need of additional fastening means. A further advantage of spring clamp 50 lies in the fact that it permits ready removal and insertion of the transformer by hand, no tools being required. In the present instance, the transformer has four insulated terminals 52 which are pressed by spring clamp 50 against four insulated contacts 53 mounted on a wall of chamber 42. Therefore, the mere insertion of transformer 49 into the chamber automatically connects the primary and secondary coils of the transformer in the amplifying system about to be described. A similar transformer 54 is mounted in chamber 45, and what has been said above on the mounting and connections of transformer 49 applies to transformer 54 without the need of repetition.

In chamber 43 is housed a cell or battery 55, which may be regarded as the filament or so-called "A" battery. A pair of spring members 56 carried by the box or framework 43 hold the battery in fixed position and yet

allow the same to be easily removed when desired. Conductors 57 are led into the chamber through a small hole and attached to the battery terminals 58.

A plate or "B" battery is supported in chamber 44, but it will not be necessary to show it, for what has been said about the mounting of the "A" battery 55 applies to the plate battery, which is indicated diagrammatically at 59 in Fig. 7.

Two amplifying tubes 60 and 61 are mounted on a suitable support 62 in the forward part of compartment 22. The structural details of support 62 need not be shown or described, for the mounting of vacuum tubes in sockets is well known. The tubes 60 and 61 are of the usual three-electrode type suitable for amplifying current impulses. The motor-board 19 has openings 63 through which the tubes project sufficiently to be grasped by the fingers for removal. Also, the openings 63 permit the insertion of new tubes without lifting the board 19. To prevent vibration of the tubes, I fasten yieldable rings 64 to the underside of the motor-board around the openings 63. The rings 64 are made of felt, rubber, leather, or other suitable material, and yieldingly grip the tubes. A small signal lamp 65 may be arranged between the tubes 60 and 61 to let the operator know that the filament circuit is on or off. A socket 66 (see Fig. 4) is fixed on tube support 62 for receiving the signal lamp 65. This lamp may, of course, be supported in any other position where it is readily visible.

On the front post 18 in compartment 23 is mounted a suitable switch 67, here shown for convenience in the form of two insulated spring contacts which are normally held closed by their own inherent tension. One of the doors (for example, door 15) carries an insulated wedge 68 arranged to enter between the switch contacts 67 and hold them apart when the door is closed, as may be seen in Fig. 4. When the door 15 is opened, the contacts 67 automatically snap together and close the circuit of filament battery 55, as will be better understood when I come to describe the circuit connections of Fig. 7. Therefore, as long as the door 15 (or 16) remains closed, the filament circuit is open and no waste of current is possible. It is obvious that switch 67 may be so arranged as to require the opening of both doors to close the switch and the closing of either door to open the switch. For this it is only necessary to have two pairs of contacts in series and a projection 68 (or its equivalent) on each door. This will be clear without additional illustration. When I, therefore, speak of a switch controlled by the doors of the cabinet, I include both a single door and a double door control. It goes without saying that switch 67 and the cooperating member 68 may be arranged in any other practical way, and these parts are mere-

ly representative of suitable switch means controlled by one or both doors of the cabinet.

Looking at Figs. 2 and 3, there is a finger piece 69 in the shape of a small knob projecting through an arcuate slot 70 in the top board 19. This finger piece controls certain switch mechanism indicated as a whole by W, which I shall now describe, reference being had to Fig. 7 where this mechanism is shown as simply as possible in a diagrammatic way. The knob 69 is fixed to a link 71 of insulating material, which is connected to a pair of arms 72 and 73 pivoted at points 74 and 75, respectively. In practice, these arms may consist of insulating bars pivoted to the underside of the motor-board and carrying contact pieces 76, 77, 78 and 79, as indicated. The two contact pieces on each arm are electrically insulated from each other. With the switch arm 72 are associated two pairs of fixed contacts or terminals 80—81 and 82—83. These terminals are so arranged that in one position of arm 72 the contact pieces 76 and 77 engage terminals 80 and 81, respectively, while in the other position of arm 72 the same contact pieces engage terminals 82 and 83, respectively. The other switch arm 73 has associated therewith two pairs of fixed contacts or terminals 84—85 and 86—87. When switch arm 72 touches the terminals 80 and 81, as just described, the switch arm 73 is in contact with terminals 84 and 85. This is the position of the switch arms shown in Fig. 7. When the switch arm 72 touches the other pair of terminals 82 and 83, the switch arm 73 engages terminals 86 and 87. I have purposely omitted to show the second position of the switch arms in Fig. 7 so as not to create confusion by the crossing of lines.

Now for the circuit connections in Fig. 7. One side of the reproducer circuit is connected by a wire 88 to the grid 89 of tube 60, and the other side of that circuit is completed through the filament 90 and connections 91 and 92. The operation of reproducer 30 causes variable voltages to be impressed on grid 89, as will be understood without further explanation. The plate electrode 93 of tube 60 is connected by a wire 94 to one terminal of the primary coil 95 of transformer 49, and the other side of that coil is connected through wire 96 to the positive terminal 97 of plate battery 59. A rheostat 98 having a controlling arm 99 is preferably inserted in the plate circuit to regulate the normal current and potential values. The rheostat is supported beneath the motor-board and the rheostat arm 99 is operated by a knob 100 on the motor-board, as shown in Fig. 2. As the knob 100 is turned to the right, the resistance 99 is gradually cut out and the ultimate effect is to increase the volume of reproduction and also to obtain the desired quality in the amplified reproduction. Different tubes may

require different plate currents for the best acoustic results in a given instrument.

The primary coil 101 of transformer 54 is connected at one side to the plate electrode 102 of tube 61, and the other side of the coil is connected by wire 103 to the positive terminal of battery 59. A conductor 104 connects the negative side of battery 59 to the filament 90 of tube 60, and a conductor 105 connects the filament 106 of tube 61 with the same side of the battery. In other words, the primary coils 95 and 101 (and therefore the plate circuits of the amplifying tubes) are connected in parallel to battery 59. The rheostat 98 is so arranged as to control the two plate circuits simultaneously when both tubes are working.

One side of filament 90 is connected to one pole of battery 55 through a wire 107 and switch 67. The other side of filament 90 is connected to a wire 108, and the other pole of battery 55 is connected to a wire 109 through the signal lamp 65 and a rheostat 110 suitably supported beneath the top board 19. The lamp 65 and rheostat 110 are connected in series. To prevent interruption of the filament circuit (or circuits) in the event that the signal lamp 65 is out of commission, I shunt the lamp with a resistance 111, which ought to be of about the same value as the resistance of the lamp. This resistance may be mounted on tube support 62. The rheostat arm 112 is operated by a knob 113, or other finger piece, on the motor-board 19 (see Fig. 2). The conductor 108 has two branches 114 and 115, which are permanently connected, respectively, to insulated contact pieces 116 and 117 carried by the pivoted switch arms 72 and 73. Conductor 109 of the filament circuit is permanently connected to a pair of fixed terminals 118 and 119. When the switch arm 72 engages contacts 80 and 81, the contact piece 116 engages terminal 118; when the switch arm is thrown over to make contact with terminals 82 and 83, the contact piece 116 engages terminal 119. Thus, in either operative position of the switch arm, the circuit of filament 90 is closed. But when the switch arm 72 is in a neutral position—that is, out of engagement with both pairs of contacts 80—81 and 82—83, the contact member 116 does not engage either of the terminals 118 and 119, so that the filament circuit is open, even if switch 67 should be closed.

The circuit of filament 106 includes a conductor 120 for connecting one side of the filament with battery 55, and a conductor 121 which is permanently connected to a fixed contact or terminal 122. When the switch arm 73 is in the position shown in Fig. 7, the contact 122 is isolated and the circuit of filament 106 is open. When the switch arm 73 is thrown over to engage the terminals 86 and 87, the contact piece 117 on arm 73 en-

gages the terminal 122 and thereby closes the filament circuit of tube 61. This means that both tubes are in operation, with the filament circuits connected in parallel.

5 The ends of the secondary coil 123 of transformer 49 are permanently connected to the contact parts 76 and 77 of switch arm 72 by wires 124 and 125. The ends of the secondary coil 126 of transformer 54 are permanently connected to the switch contacts 86 and 87 by conductors 127 and 128. The switch contacts 80 and 84 are connected by a wire 129, and switch contacts 81 and 85 are connected by a wire 130. Switch terminal 82 is connected by a wire 131 to the grid 132 of tube 61. The fixed contact 83 is connected by a wire 133 to the conductor 105, which leads from the filament 106. The conductors 38 and 39 of the electromagnetic driving unit 35 are connected, respectively, to the contact parts 78 and 79 of switch arm 73.

10 I may insert here, in passing, that when I refer to an electric connection as a wire, I use the word as a convenient way to include any practical form of electrical connector, whether it be a wire, rod, plate, or what not.

15 The operation of the amplifying system disclosed in Fig. 7 is the following: Assuming switch 67 closed and switch mechanism W in the position illustrated, the plate circuit of tube 60 is traced from the positive terminal 97 of battery 59, through rheostat 98 and conductor 96, through the primary coil 95 to plate electrode 93, across the electronic path 20 in tube 60 to one side of filament 90, then through wires 91 and 104 back to the other side of battery 59. The filament circuit of tube 60 is from one side of battery 55 through the closed switch 67 and conductor 107 to filament 90, through the filament to wire 91, then through wires 108 and 114 to contact piece 116, which is on terminal 118, from there through wire 109, rheostat 110 and signal lamp 65 (also through resistance 111 if 25 present) to the other side of battery 55. The circuit of the secondary coil 123 follows this path: from one end of the coil through wire 124 to contact member 76 of switch arm 72, through wire 129 to switch terminal 84, from 30 there through lead 38 to the electromagnetic mechanism of unit 35, through the return lead 39 to contact part 79, through wire 130 to switch terminal 81, then through contact part 77 and wire 125 back to the coil.

35 It will be clear from the preceding description that, when the switch mechanism W is in the position illustrated in Fig. 7, the second amplifying tube 61 is entirely cut out and the diaphragm 32 operates on a single stage 40 of amplification. This fact is indicated to the operator by the "one" position of controlling knob 69, as shown in Fig. 2. To obtain a two-stage amplification, the operator moves knob 69 over to the other end of slot 70 into 45 the "two" position, as indicated by a dotted

circle 69^a in Fig. 2. This movement of knob 69 rocks the switch arms 72 and 73 into contact with the other pairs of terminals 82—83 and 86—87, as previously explained. Both tubes are now in operation. The filament circuit of tube 60 is traced as before, except that from contact piece 116 we now go to terminal 119. The filament circuit of tube 61 is from one side of battery 55 through wire 120 to filament 106, from there through wire 121 to terminal 122, which is now engaged by contact piece 117, from there through wires 115 and 114 to contact piece 116, and then home to battery 55 through the path already traced for filament 90. The two filament circuits are therefore connected in parallel with battery 55. The plate circuit of tube 60 is the same as before. The plate circuit of tube 61 is from the positive side 97 of battery 59 through conductor 103, through primary coil 101 to plate electrode 102, across the electronic path in tube 61 to one side of filament 106, and through conductor 105 back to the battery. It is clear from this that the plate circuits, and therefore the circuits of the primary coils 95 and 101, are connected in parallel when both tubes are in operation. The circuit of secondary coil 123 is completed thus: from one end of the coil to wire 124 and contact part 76, which now touches the terminal 82, through connection 131 to grid 132 of tube 61, through one side of filament 106, through conductors 105 and 133 to switch terminal 83, which is now engaged by contact member 77 of switch arm 72, then through wire 125 back home to coil 123. The circuit last traced is the grid circuit of tube 61, and the electric impulses in this circuit produce greatly amplified current impulses in the circuit of primary coil 101. The circuit of secondary coil 126, when the contact members 78 and 79 engage the switch terminals 86 and 87, respectively, passes through the operating coil or coils of the driving unit 35 by means of connections 38 and 39 as already mentioned.

When the knob 69 is moved to an intermediate position, as indicated in Fig. 2 by a dotted circle 69^b, the switch arms 72 and 73 stand midway between the fixed terminals 115 of the switch and out of contact therewith, as will be clear without further illustration. In other words, the "off" position of knob 69 assures the operator that all circuit connections are open and no battery current is being needlessly consumed. Suitable means may be provided to hold the switch arms in actuated position, so as to obviate the risk of accidental displacement when the phonograph is carried about or otherwise unexpectedly jarred. As a practical example of such retaining means, I have shown in Fig. 7 a spring member 134 comprising a corrugated strip or wire secured at its ends 135. This strip or wire has as many corrugations 130

or recesses 136 as there are positions of the switch arms 72 and 73. The link 71 carries a cam 137 adapted to enter the recesses in spring member 134, which presses against the cam enough to hold the switch in actuated position. The spring member 134 is sufficiently yielding to permit movement of the switch arms 72 and 73 from one position to the other by a slight pressure on knob 69.

10 I have purposely shown the lid 12 of the cabinet deeper than actually necessary, so as to show how a stack of records 138 may be attached to the inside of the lid. For this purpose the lid carries a screw rod 139 on which the records are strung and clamped in place by a wing nut 140. A washer or small disk 141 is preferably interposed to prevent injury to the records when the nut is screwed home. In Fig. 1, the dotted outline 42 indicates the depth of a stack of records that may be carried in the cabinet without interfering with the closing of the lid. The rod 139 is, of course, made long enough to hold the desired number of records. In 20 the present embodiment I have the turntable 25 to be ten inches in diameter, but the machine operates equally well on 12-inch records, and these large records can be supported in the lid without interference by the 25 producer arm 29. The record 31 shown in Fig. 2 is supposed to be a 10-inch record, and a 12-inch record extends to the dotted circle 142, which is clear of reproducer arm 29 when the latter is in idle or rest position. To insure this position of arm 29 before the lid is closed, I provide a rest 143 on the motor-board adapted to engage the reproducer arm and hold it until released. In the present instance, the rest 143 terminates in a pair 30 of spring fingers 144, between which the arm 29 is held clamped without danger of dis- placement during transportation of the machine. Any other practical means may be used to hold the reproducer arm in fixed position out of the way of the records in the 35 lid.

A handle 146 is fixed to the body section 10 of the cabinet in such position that the machine as a whole feels pretty well balanced when held by the handle. When the outer box of the machine is made circular, as herein shown, I provide a foot piece 147 opposite the handle to act as a stand or supporting base for the box in upright position. 50 The straight edge of this foot piece affords the additional advantage of permitting the use of a long substantial hinge 148 for the lid 12.

Attention is called to the symmetrical arrangement of the batteries and transformers in compartment 22, so as to obtain a substantially balanced distribution of the weight of those parts on either side of the carrying handle. This is clear from Fig. 2. The batteries, which are the heaviest parts in the

cabinet, are placed near the base 147 to increase the stability of the case as a whole when standing upright. The dimensions of the outer case will obviously vary with the size of the diaphragm, with the depth of the chamber necessary to accommodate the downwardly extending board 21 and the upwardly pointing diaphragm 32, and also with the depth of lid 12 to accommodate a certain number of records. An 18-inch diaphragm, 75 properly constructed and operated, will give a reproduction as loud as that of a cabinet phonograph with a big horn and of better tonal quality. A diaphragm of that size can be housed in a cylindrical box not more than 20 or 21 inches across. For smaller and lighter machines of less volume, a 10-inch or 12-inch diaphragm is sufficient and only one stage of amplification need be provided for. A machine like that shown in 80 the drawings can be housed in a carrying case about the size of a woman's hat-box. Of course, the case need not be cylindrical, but may be square, or rectangular, or of any other practical shape and design. Also, the 85 case containing the mechanism may be constructed as part of a large household cabinet.

Portable mechanical phonographs of the horn type, even the most expensive makes, 90 are incapable of giving a reproduction of good volume and quality, mainly because the small carrying case affords no room for an adequate horn or amplifying chamber. In the electric phonograph of my invention as 95 applied to portable machines, a hornless loud-speaking diaphragm is mounted horizontally at the bottom of a small box, and electric amplifying mechanism is housed in a shallow chamber below the motor-board, thereby producing a phonograph of hand-baggage size and weight, and yet a machine capable of great volume and fine quality of reproduction hitherto unobtainable in portable phonographs. The ease with which the 100 volume of reproduction may be electrically regulated in the phonograph of my invention adds to its practical usefulness. As far as I know, I am the first to provide an electric 105 phonograph of the portable type, and I 110 therefore claim certain features of my invention in a fundamental way.

I claim as my invention:

1. A portable electric phonograph comprising, in combination, a carrying case having a base and a topboard, said case being of less height than length or width, whereby said case is portable, means to provide an upper compartment below the topboard and a lower compartment above the base, said lower compartment forming a sound chamber freely open to the outer air, a loud-speaking diaphragm mounted horizontally in said sound chamber, electromagnetic means for operating said diaphragm, an electric reproducer 125

5 operatively mounted over the topboard for playing records, and electric apparatus in said upper compartment for amplifying the electric impulses of said reproducer and transmitting them to said diaphragm operating means.

10 2. In a hornless electric phonograph, an outer casing having a top board and a base, a loudspeaking diaphragm mounted in horizontal position on said base, said casing being open around the diaphragm for the passage of sound into the outer air, a unit in said casing for operating said diaphragm, an electric reproducer operatively mounted over the top board for playing records, electric devices supported in the space between the top board and the diaphragm, and connections whereby said devices constitute a system for amplifying the electric impulses of said reproducer and transmitting them to said unit.

15 3. An electric phonograph comprising, in combination, a casing provided with a top board and a motor-driven turntable, a loud-speaking diaphragm mounted horizontally at the bottom of said casing, a transverse partition arranged in said casing between said top board and said diaphragm, said top board and partition forming a practically closed compartment, the space or chamber between said partition and said diaphragm being open to the outer air, an electromagnetic unit in said casing for operating said diaphragm, said partition being adapted to deflect sound waves coming from said diaphragm into the outer air, an electric reproducer operatively mounted over said top board for playing records on the turntable, and electric devices housed in said compartment and so connected as to constitute a self-contained system for transmitting the electric impulses of said reproducer to said unit.

20 4. In an electric phonograph, an outer casing provided with a top board and with an inner transverse partition which divides the casing into an upper compartment and a lower compartment, said upper compartment between the top board and the partition being practically closed, a door for the lower compartment to open the same to the outer air, said door when closed forming part of the outer casing structure, a loudspeaking diaphragm mounted in the lower compartment, an electromagnetic unit in said casing for operating said diaphragm, said partition being adapted to deflect sound waves coming from the diaphragm into the outer air and said door being adjustable in open position to deflect sound waves into the desired direction, an electric reproducer operatively mounted over said top board, and electric devices supported in said upper compartment and so connected as to constitute a system for transmitting the electric impulses of said reproducer to said unit.

25 5. An electric phonograph comprising, in

combination, a casing provided with a top board and a motor-driven turntable, a cone diaphragm mounted horizontally at the bottom of said casing with the apex of the cone pointing upwardly, the casing around said diaphragm being open to the outer air for the passage of sound waves, a cone-shaped partition arranged transversely in said casing between the top board and said diaphragm with the apex of the partition pointing downwardly toward the diaphragm, whereby said partition acts to deflect sound waves coming from the diaphragm into the outer air, an electromagnetic unit in said casing for operating said diaphragm, an electric reproducer operatively mounted over said top board for playing a record on the turntable, and electric devices supported in the compartment between said top board and partition for transmitting the electric impulses of said reproducer to said unit.

30 6. In an electric phonograph, an outer casing having a top board and a base, a loud-speaking diaphragm mounted on said base, said casing being open around the diaphragm for the passage of sound into the outer air, a unit in said casing for operating said diaphragm, an electric reproducer operatively mounted over the top board for playing records, electric devices supported in the space between the top board and the diaphragm for transmitting the electric impulses of said reproducer to said unit, and means arranged in said casing between said devices and said diaphragm for deflecting sound waves into the outer air.

35 7. A portable self-contained electric phonograph comprising an outer casing having a top board and a base, an electric reproducer operatively mounted over said top board, a hornless loudspeaking diaphragm mounted horizontally on said base, an electromagnetic unit for operating said diaphragm, a transverse partition in said casing between the top board and said diaphragm, said top board and partition forming a practically closed compartment, and means in said compartment for transmitting the electric impulses of said reproducer to said unit.

40 8. A portable self-contained electric phonograph comprising a normally closed outer case or box having three compartments, an upper or lid compartment housing an electric reproducer above the top board and having means for supporting a stack of records without interference by said reproducer, a bottom compartment containing a hornless loud-speaking diaphragm and having one or more doors to open and close the space above the diaphragm, an electromagnetic unit for operating said diaphragm, and an intermediate compartment directly below the top board for containing electric devices adapted to form a self-contained system for transmit-

ting the electric impulses of said reproducer to said unit.

9. In an electric phonograph, an outer casing having a top board and a base, a loud-speaking diaphragm mounted on said base, said casing being open around the diaphragm for the passage of sound into the outer air, a unit in said casing for operating said diaphragm, an electric reproducer operatively mounted over the top board for playing records, a plurality of separate chambers or recesses extending below the top board and open at the top for access, a cover for each of said chambers adjustably mounted on the top board for opening and closing the chamber below, an electric device mounted in each chamber independently of the other devices, and means for so connecting said devices that they constitute a system for transmitting the electric impulses of said reproducer to said unit.

10. An electric phonograph comprising an outer casing having a top board and a base, an electric reproducer operatively mounted over said top board, a hornless loudspeaking diaphragm mounted horizontally in the space between the top board and said base, an electromagnetic unit for operating said diaphragm, multi-stage mechanism in said cabinet for amplifying the electric impulses of said reproducer and transmitting them to said unit, and a hand-operable switch in said cabinet for controlling the number of stages of amplification of said transmitting mechanism.

11. In an electric phonograph, a cabinet having a chamber for the passage of sound into the outer air, a door for closing and opening said chamber, electric reproducing mechanism in said cabinet, said mechanism including a plurality of amplifying tubes, a switch in the filament circuits of said tubes adapted to be opened and closed by said door when the latter is closed and opened, and a separate hand-operated switch for selectively connecting one or more tubes in circuit, said switches being connected in series in the filament circuit of each tube.

12. In an electric phonograph, a cabinet having a top board, electric reproducer mechanism in said cabinet, said mechanism including a transformer, a support for said transformer below the top board, said support being accessible through an opening in the top board, means engaging said transformer for automatically holding it in predetermined position upon insertion thereof through said opening into said support, means for automatically connecting said transformer in circuit when the same is properly positioned in said support, and a movable cover for said opening mounted on the top board.

13. In an electric phonograph, an outer casing having a top board and a base, a loud-speaking diaphragm mounted on said base,

said casing being open around the diaphragm for the passage of sound into the outer air, a unit in said casing for operating said diaphragm, an electric reproducer operatively mounted over the top board for playing records, electric devices supported in the space between the top board and the diaphragm for transmitting the electric impulses of said reproducer to said unit, said devices including a plurality of amplifying tubes, switch mechanism in said casing for selectively connecting one or more of said tubes for operation, and means for operating said switch mechanism.

14. In an electric phonograph, a cabinet having a top board and a base, a cone diaphragm mounted on said base, there being a space between the diaphragm and the base, an electromagnetic unit fixed on said base in said space and operatively connected to said diaphragm, said base and the parts mounted thereon being attachable to and removable from the body of said cabinet as a unitary member, electric devices supported in said cabinet between said diaphragm and the top board, an electric reproducer operatively mounted on the top board, connections whereby said devices operate to amplify the electric impulses of said reproducer and transmit the same to said unit, said cabinet being open for the passage of sound from said diaphragm to the outer air, and means operable by a finger piece on the top board for controlling the degree of amplification of said devices.

15. An electric phonograph comprising, in combination, a casing provided with a top board and a motor-driven turntable, a loud-speaking diaphragm mounted horizontally at the bottom of said casing, a transverse partition arranged in said casing between said top board and said diaphragm, said top board and partition forming a practically closed compartment, the space or chamber between said partition and said diaphragm being open to the outer air, an electromagnetic unit in said casing for operating said diaphragm, said partition being adapted to deflect sound waves coming from said diaphragm into the outer air, an electric reproducer operatively mounted over said top board for playing records on the turntable, electric devices supported in said compartment for transmitting the electric impulses of said reproducer to said unit, said devices including a plurality of amplifying tubes, switch mechanism in said compartment for selectively connecting one or more of said tubes for operation, and a finger piece on the top board for operating said switch mechanism.

16. A portable self-contained electric phonograph comprising, in combination, a substantially cylindrical outer casing provided with a lid and with a supporting stand.

at one side, a top board at the upper end of said casing and a transverse partition within the casing to form a closed compartment below the top board, a plurality of openings arranged radially in the top board, said openings lying practically in that half of the top board which extends toward said stand, a movable cover on the top board for each opening, a plurality of supports in said compartment arranged in line with said openings, an electric device carried by each support, said devices being insertable and removable through said openings without disturbing the top board, the arrangement of said devices being such that their weight serves to stabilize the casing when resting on its stand, a hornless loudspeaking diaphragm mounted at the bottom of said casing, one or more doors on said casing for closing and opening the chamber above said diaphragm, an electromagnetic unit in said casing for operating said diaphragm, an electric reproducer operatively mounted over the top board, and connections whereby said electric devices constitute a self-contained system for transmitting the electric impulses of said reproducer to said unit.

17. In an electric phonograph, an outer casing provided with a top board and with an inner transverse partition which divides the casing into an upper compartment and a lower compartment, said upper compartment between the top board and the partition being practically closed, a door for the lower compartment to open the same to the outer air, a loudspeaking diaphragm mounted in the lower compartment, an electromagnetic unit in said casing for operating said diaphragm, said partition being adapted to deflect sound waves coming from the diaphragm into the outer air and said door being adjustable in open position to deflect sound waves into the desired direction, an electric reproducer operatively mounted over said top board, electric devices supported in said upper compartment for transmitting the electric impulses of said reproducer to said unit, said devices including an amplifying tube, and means controlled by said door whereby the filament circuit of said tube is automatically opened when the door is closed and whereby said circuit is automatically closed when the door is opened.

18. In an electric phonograph, an outer casing provided with a top board and with an inner transverse partition which divides the casing into an upper compartment and a lower compartment, said upper compartment between the top board and the partition being practically closed, a door for the lower compartment to open the same to the outer air, a loudspeaking diaphragm mounted in the lower compartment, an electromagnetic unit in said casing for operating said diaphragm, said partition being adapted to

deflect sound waves coming from the diaphragm into the outer air and said door being adjustable in open position to deflect sound waves into the desired direction, an electric reproducer operatively mounted over said top board, electric devices supported in said upper compartment for transmitting the electric impulses of said reproducer to said unit, said devices including a plurality of amplifying tubes, switch mechanism in the upper compartment for selectively connecting one or more of said tubes for operation, a finger piece on the top board for operating said switch mechanism, and a switch controlled by said door for opening the filament circuits of said tubes when the door is closed and closing said circuits when the door is opened.

19. An electric phonograph comprising a cabinet having a top board and a base, a loudspeaking diaphragm mounted on said base, an electromagnetic unit for operating said diaphragm, a transverse partition between said top board and diaphragm to form a practically closed compartment, a door for opening the casing around said diaphragm for the passage of sound into the outer air, said door when closed forming part of the outer casing structure, an electric reproducer operatively mounted over said top board, electric devices mounted in said closed chamber below the top board which is provided with openings to permit ready access to said devices, movable covers for normally closing said openings, means for so connecting said devices that they constitute a system for transmitting the electric impulses of said reproducer to said unit, a switch in said system, and means operated by said door for holding said switch open as long as the door remains closed, said last-named means automatically closing said switch when the door is opened.

20. A portable self-contained electric phonograph comprising a normally closed outer box which consists of a body part and a hollow lid, a top board at the upper end of said body part and a base at the other end thereof, a motor-driven turntable supported over the top board, a hornless loudspeaking diaphragm mounted on said base and of substantially the same size as the base, an electromagnetic unit for operating said diaphragm, a transverse partition between said top board and diaphragm to form a practically closed chamber, a door for opening the casing around said diaphragm for the passage of sound into the outer air, said door when closed forming part of the outer casing structure, an arm mounted on the top board to swing horizontally over a record on the turntable, an electric reproducer carried by said arm, means for holding said arm in rest position away from the turntable, electric devices mounted in said closed chamber, means for so connecting said devices that they constitute

- a self-contained system for transmitting the electric impulses of said reproducer to said unit, and means for mounting a stack of records on the inside of said lid, said stack of records extending inwardly beyond the reproducer arm when the lid is closed and said reproducer arm in rest position being out of the way of said records. 5
21. In an electric phonograph, a case having a top board, an electric reproducer mounted on said top board, a movable section normally forming part of said top board, a compartment below said section for receiving electric apparatus operatively connected with said reproducer, said section forming a movable cover for said compartment, and a loudspeaking diaphragm mounted in said case and having an electromagnetic driving unit connected with said apparatus. 10
22. A hornless electric phonograph comprising an outer casing having a topboard and a base, means to provide a closed compartment below said topboard, the space between said compartment and said base providing a sound chamber open to the outer air, a loudspeaking diaphragm mounted horizontally in said chamber, a driving unit for said diaphragm, an electric reproducer operatively mounted over the topboard for playing records, and electric devices supported in said closed compartment for transmitting the electric impulses of said reproducer to said driving unit. 15
23. A hornless electric phonograph comprising an outer casing having a topboard and a base, means to provide a closed compartment below said topboard, the space between said compartment and said base providing a sound chamber open to the outer air, 20 a cone diaphragm mounted horizontally in said chamber, a driving unit for said diaphragm, an electric reproducer operatively mounted over the topboard for playing records, electric devices supported in said closed compartment for transmitting the electric impulses of said reproducer to said driving unit, and a conical board arranged horizontally in said casing opposite said diaphragm to deflect sound waves into the open air. 25
24. In an electric phonograph, a cabinet having a top board and a chamber below said top board for the passage of sound into the outer air, a door for opening and closing said chamber, electric reproducing mechanism including an amplifying tube with a filament circuit, a pair of switches connected in series in said filament circuit, means whereby one of said switches is opened and closed by said door when the latter is closed and opened, and hand-operable means carried by the cabinet for actuating the other switch. 30
25. In a hornless electric phonograph, an outer casing having a top board and a base, a loudspeaking diaphragm mounted in hori- 35
- zontal position on said base, said casing being open around the diaphragm for the passage of sound into the outer air, a unit in said casing for operating said diaphragm, an electric reproducer operatively mounted over the top board for playing records, an electric means in said casing below the top board for establishing an operative connection between said reproducer and said driving unit. 40
